176,486

TOY CONVEYOR

Albert Ruth, Gering, Nebr.

Application May 5, 1955, Serial No. 35,848

Term of patent 14 years

(Cl. D34—15)

Fig. 1

Fig. 2

Fig. 3

Figure 1 is a front perspective view of a toy conveyor, showing my new design;

Figure 2 is a rear perspective view thereof; and

Figure 3 is a front end elevational view of the same.

I claim:

The ornamental design for a toy conveyor, as shown.

References Cited in the file of this patent

UNITED STATES PATENTS

D. 169,310 Fullerton ----- Apr. 14, 1953